Primary Examiner—Brian N. Vinson(74) *Attorney, Agent, or Firm*—Quarles & Brady LLP(57) **CLAIM**

The ornamental design for a wall mountable support, as shown and described.

DESCRIPTION

In a preferred embodiment, the nature of this product is a wall mountable support, such as a robe hook, a towel ring, a toilet paper holder, a single rung towel bar, a double rung towel bar, or an escutcheon for use in supporting wall mountable items.

FIG. 1 is a right, top, front perspective view of a wall mountable support according to my new design;

FIG. 2 is a front elevational view thereof;

FIG. 3 is a right side elevational view thereof, the left side elevational view being a mirror image the right side shown;

FIG. 4 is a top plan view thereof; the bottom plan view thereof being identical to the top view shown; and,

FIG. 5 is a rear elevational view thereof.

The broken line representations of mounting structure in FIGS. 1, 2, and 3 are for the purpose of illustration only, and form no part of the claimed design.
